COSMETIC APPLICATOR

Charles A. Mureau, Los Angeles, Calif.

Application August 4, 1939, Serial No. 288,330

2 Claims. (Cl. 15—137)

This invention relates to cosmetic applying devices and relates more particularly to devices for containing and applying paste lip rouge, mascara, etc. A general object of this invention is to provide a practical and effective cosmetic applicator of this nature.

Another object of this invention is to provide a cosmetic applicator embodying a container for a supply of the cosmetic, a novel brush means for applying the cosmetic and an improved ejecting means for ejecting the cosmetic into the brush means.

Another object of this invention is to provide a device of the character mentioned in which a single one-piece body forms the cosmetic container, the head for supporting the brush means and the housing and support for the ejecting means.

Another object of this invention is to provide a cosmetic applying device in which a replacement supply of the cosmetic may be introduced into the body without disturbing the applying means or brush means. In the applicator of the present invention the cosmetic is supplied through the end of the body opposite the brush means so that there is no necessity for removing or disturbing the brush means.

Another object of the invention is to provide a novel brush means that is simple and inexpensive to manufacture and that may be readily secured in the applicator body without resorting to the use of screw threads.

A further object of this invention is to provide a cosmetic applicator of the character mentioned in which the ejecting means embodies a minimum number of simple, inexpensive parts and is conveniently operable by merely turning a knob at the outer end of the body.

The various objects and features of my invention will be fully understood from the following detailed description of a typical preferred form and application of the invention, throughout which description reference is made to the accompanying drawing, in which:

Fig. 1 is a side elevation of the improved cosmetic applicator of the invention. Fig. 2 is a view similar to Fig. 1 with the cover or cap removed. Fig. 3 is an enlarged central longitudinal detailed sectional view of the applicator. Fig. 4 is a transverse detailed sectional view taken as indicated by line 4—4 on Fig. 3, and Fig. 5 is an enlarged side elevation of the brush means removed from the body.

The cosmetic applicator of the present invention may be said to comprise, generally, a body

10 forming a container for a supply of the cosmetic C, applying means 11 projecting from the forward end of the body 10 for applying the cosmetic C, and means 12 for forcing or ejecting the cosmetic C from the body 10 to the applying means 11.

The body 10 is a hollow or tubular member that serves as a container for the cosmetic C and that carries the other elements of the device.

10 In the preferred construction the body 10 is an elongate one-piece or integral member. In practice the body 10 may be formed of any suitable or selected material, for example, it may be formed of metal or of any of the so-called plastics. A central longitudinal opening 13 of substantially uniform diameter enters the body 10 from its outer or rear end. The opening 13 forms the cosmetic reservoir or chamber. The forward portion 14 of the body 10 is reduced in diameter to provide an external annular shoulder 15 and this reduced body portion 14 tapers or rounds inwardly at the forward extremity of the body. A socket 16 of somewhat reduced diameter extends forwardly in the body portion 14 and an opening 17 of still smaller diameter continues forwardly from the socket 16 to the forward end of the body. A rearwardly facing shoulder 18 occurs on the inner surface of the body 10 where the socket 16 joins the opening 13. A removable cover or cap 19 is applied to the reduced forward portion 14 of the body 10 to enclose and protect the applying means 11 as will be further described. The inner part of the cap 19 may be flush with the external surface of the body 10 while the forward portion of the cap may be stepped or graduated as illustrated. It is to be observed that the body 10 is of simple, inexpensive construction.

The applying means 11 is provided to facilitate the application of the cosmetic C and is particularly useful in the application of lip rouge, mascara, and the like. In the preferred form of the invention the means 11 is in the nature of a brush means particularly adapted for the handling of paste rouges, etc. The means 11 is carried in the reduced forward portion 14 of the body 10 and includes a tubular shell 20 preferably formed of metal. The shell 20 is tapered or frusto-conical and is received in the socket 16 with suitable clearance. The forward end of the shell 20 is adjacent the inner end of the opening 17 and the internal diameter of this end of the shell is substantially the same as the diameter of the opening 17.

55 The brush means or applying means 11 further

includes a brush tuft or brush 21 made up of bristles set in the shell 20. The bristles constituting the brush 21 are preferably soft and fine and of substantial length. The inner portion of the brush 21 is secured in the conical shell 20 by setting the brush bristles in a body of wax and rosin. I have found that a mixture of wax and rosin or synthetic wax in suitable proportions is unaffected by the cosmetics and does not flake away or produce hard particles that may become mixed with the cosmetics. The bristles set or embedded in the wax and rosin or synthetic wax mixture in the tapering shell 20 are securely held in place and forward pressures against the brush tend to tighten the brush in the shell. The bristles constituting the brush 21 are sufficiently long to extend through the opening 17 and project a substantial distance from the forward end of the body 10. The wall of the opening 17 supports and confines the intermediate portion of the brush 21 and centralizes the projecting part of the brush 21. It will be observed that the active outer portion of the brush that receives the cosmetic is out of contact with the shell 20 and all other metal parts.

The means 11 further includes a shank or tube 22 extending centrally through the brush 21. The tube 22 has an enlarged part or flange 23 tightly fitting the socket 16 and the forward portion of the tube 22 is tapered. The inner end of the brush 21 and the inner end of the shell 20 may engage against the forward face of the flange 23. The longitudinal opening 24 of the tube 23 communicates with the cosmetic opening 13 and discharges into the brush 21 at the forward end of the device. In the preferred construction the forward end of the tube 22 is substantially flush with or slightly inset from the forward extremity of the body 10. The longitudinal opening 24 of the tube 22 is large in diameter to assure a free flow of the cosmetic. However, the forward end portion of the tube is tapered and reduced in diameter to concentrate the cosmetic discharge. The outer portion of the tube 22 may be reduced or tapered by a spinning operation. In constructing the brush means or applying means 11 the brush 21 is first secured or set in the tapering inner part of the shell 20 and a suitable pointed tool is heated and forced through the wax and rosin mixture in which the brush is set. The opening thus formed is adapted to receive the tube 22 and the tube is immediately arranged in this opening. It is to be noted that the brush 21 is rather closely confined between the tube 22 and the forward portion of the shell 20 so that the brush 21 is dependably centralized and sustained. The flange 23 tightly fitting the socket 16 secures the means 11 in the body. It will be observed that the tube 22 operates to deliver the cosmetic from the body opening 13 to the interior of the brush 21 at the forward extremity of the body 10 to be immediately available for application.

The ejecting means 12 is provided to eject or force the cosmetic C from the body opening 13 to the interior of the brush 21. The means 12 includes a plunger 25 on the forward end of a threaded stem 26. The stem 26 is of substantial length and is threaded from adjacent the plunger 25 to its rear end. An annular groove 27 is provided in the plunger 25 and a washer or sealing element 28 of leather, rubber, or the like, is sprung or set into the groove 27. The sealing element 28 may be split to facilitate its insertion in the groove 27 and the groove is of sub-

stantial depth to dependably retain the sealing element. The peripheral part of the sealing element 28 slidably seals with the wall of the body opening 13. A longitudinal key or flat tangential surface 29 is provided on the wall of the body opening 13. The surface 29 preferably extends from the rear extremity of the body 10 to the shoulder 18. A flat tangential surface 30 is formed on the periphery of the plunger 25 and slidably cooperates with the surface 29. The sealing element 28 is suitably shaped to cooperate with the surface 29. The cooperation of the surface 29 and the surface 30 holds the plunger 25 and the stem 26 against rotation. The shoulder 18 limits the forward movement of the plunger 25.

The ejecting means 12 further includes a retainer or cap 31. Rather coarse threads 32 removably secure the cap 31 on the rear portion of the body 10. The cap 31 is provided with a central longitudinal opening 33. An operating knob 34 is disposed at the outer end of the cap 31 and has a socket 35 aligned with the opening 33. The knob 34 is shaped and formed for convenient operation. In the case illustrated the knob 34 is tapered and its periphery is provided with spaced grooves 36. The knob 34 rides or bears on the outer surface of the cap 31. A tube 37 is secured to the knob 34. In practice the tube 37 has a reduced roughened or knurled part 40 pressed or force-fitted in the socket 35. The tube 37 has an annular shoulder 41 engageable with the inner or forward surface of the cap 31. The cooperation of the knob 34 with the outer surface of the cap and the cooperation of the shoulder 41 with the inner surface of the cap prevent longitudinal movement of the knob and tube 37. The tube 37 is of substantial length and extends forwardly in the body 10 to receive the plunger stem 26. The major portion of the tube 37 receives the stem 26 with substantial clearance. The forward part 38 of the tube 37 is reduced in diameter and has an internal thread mating with the thread of the stem 26. The construction just described promotes the economical manufacture of the means 12 as it makes it unnecessary to form a long thread in the tube 37. It will be seen that turning of the knob 34 results in threading or longitudinal movement of the stem 26 and the plunger 25.

In the use or operation of the device of the invention the opening 13 normally contains a supply of the cosmetic C and the cap 19 is normally in position on the body portion 14 where it covers and protects the brush 21. When it is desired to employ the device the cap 19 is removed and the operating knob 34 is turned. This turning or rotation of the knob 34 results in forward movement of the stem 26 and plunger 25. The plunger 25 moving forwardly in the body opening 13 ejects or forces the cosmetic through the opening 24 into the brush 21. The cosmetic thus supplied to the brush may then be applied. The body 10 of course constitutes a handle for the brush means 11 and the brush 21 being formed of soft, fine bristles may be employed to effectively apply the cosmetic. After use the cap 19 may be replaced so that the device may be carried without soiling the hands, clothing, etc. The brush 21 is effectively protected by the cap 19.

After repeated use the supply of cosmetic C may become exhausted and it may be desired to replenish the supply. To accomplish this the cap 32 is rotated with respect to the body 10 to

unthread it from the body. When the cap 32 is free from the body 10 the assembly of the cap, the knob 34, tube 37, plunger 25, etc., is withdrawn from the body. A replacement supply of the cosmetic C in the form of a cartridge or in any other form is then inserted in the opening 13 and the cap 32 is re-applied to the body 10 to condition the ejecting means 12 for operation.

Having described only a typical preferred form and application of my invention, I do not wish to be limited or restricted to the specific details herein set forth, but wish to reserve to myself any variations or modifications that may appear to those skilled in the art or fall within the scope of the following claims.

Having described my invention, I claim:

1. In a cosmetic applying device, a body having a cosmetic reservoir and an opening of reduced diameter leading from the reservoir to an end of the body, a conical shell arranged in the body with its small end facing and spaced from the opening, a brush tuft set in the shell and extending through the opening to project from said end of the body, the wall of the opening confining and bracing the brush tuft in a zone spaced outwardly from the shell, a tube passed forwardly through the conical shell to extend into the brush tuft to wedge the tuft in the shell and leading

outwardly to terminate immediately adjacent said end of the body, and an enlargement on the tube at the inner end of the shell press fitted in the body to mount the tube, brush and shell in the body.

- 5 2. In a cosmetic applying device, a one piece body having a cosmetic reservoir, a reduced socket at one end of the reservoir and an opening of reduced diameter leading from the socket 10 to an end of the body, a frusto-conical shell arranged in the socket with its small end and spaced from the opening, a brush tuft set in the shell and extending through the opening to project from said end of the body, the small end of 15 the shell confining and bracing the tuft, a tube inserted forwardly through the shell from its inner end to tightly wedge the brush tuft in the frusto-conical shell and leading outwardly to have its outer end immediately adjacent said end 20 of the body, the tube being in spaced concentric relation to the wall of said opening whereby the brush is confined, supported and centered by the tube and the wall of the opening, and an enlargement on the tube at the inner end of the shell force fitted in the socket to mount the tube, brush and shell in the body.
